UNITED STATES PATENT OFFICE

GEORGE A. CUMBERLAND, OF WISCONSIN RAPIDS, WISCONSIN, ASSIGNOR OF ONE-FOURTH TO MARVIN S. KING, OF WISCONSIN RAPIDS, WISCONSIN

PAPER PULP SEPARATOR

Application filed January 6, 1931, Serial No. 507,004. Renewed August 29, 1932.

This invention relates to an improved pulp separator such as is particularly adapted for use in paper manufacturing plants, and it has particular reference to an improved process and means for conditioning pulp products, where the process requires the extraction of water so as to modify or change the consistency of the pulp.

I am aware of the fact that the separation of water from the relatively thick pulp product through the use of mechanical separators and machinery is not broadly new. As a matter of fact, it is common practice to utilize what is known as a pulp decker for the purpose.

It is a matter of common knowledge therefore that it is general or universal practice in the storage of pulp to extract the major proportions of water and to subsequently add water to the extracted pulp at the time the latter is ready to be put on the screen for the manufacturing of paper. This method has been adapted in order to economize on the storage of relatively thick pulp products.

As a general rule, the present form of deckers now in substantially universal use have an open-ended cylinder located for rotation in an appropriate hopper or vat. It is customary to mount the cylinder on a solid rotating shaft. The surface of the cylinder is of a laminated porous type and allows the water to pass through said surface and to be discharged through the open ends of the cylinder. This separation of water causes the pulp to adhere to the somewhat adhesive surface of the cylinder after which it is picked up by the couch roll. It is then doctored off for storage purposes.

In this operation, there is a so called deckle strap, either of rubber or felt, which serves to close off the open end of the cylinder from the liquid in the vat. Unfortunately however, these straps are subject to disarrangement and breakage and are frequently out of order, thus allowing the liquid in the vat, which contains pulp, to escape into the effluent water.

The concensus of opinion is that these old types of deckers are continuously getting out of adjustment, so that the strap must be re-

placed from time to time. This means a stoppage in the operation of the decker. Moreover, because of the construction of the present-day deckers, the stress is not uniform and the cylinders and straps get out of alinement 55 which causes additional repairs and frequent rebuilding of the cylinder surface.

With the foregoing objections and defects in mind, I have evolved and produced an improved and seemingly more efficient structure 60 for accomplishing the result in a more expeditious, practical, and economical manner.

The specific structural organization constituting the novelty of this improved contribution to the art will become more readily apparent from the following description and drawings.

In the drawings:

Figure 1 is a top plan view of an improved decker developed and constructed in accordance with the present inventive conception. 70

Figure 2 is a longitudinal vertical sectional view on the line 2-2 of Figure 1.

Figure 3 is a transverse vertical section on the line 3-3 of Figure 1. 75

Figure 4 is a transverse section through the improved cylinder.

Figure 5 is a fragmentary sectional view thereof.

In the drawings, the vat or container in 80 general is denoted, as a whole, by the numeral 6. This is generally in the form of an open-top rectangular container. In accordance with the present invention, the opposite ends are provided with fixtures of appropriate design carrying suitable packing glands 7. Beyond these packing glands and on the exterior of the vat are standards 8 whose upper end portions are provided with 85 upper and lower bearings 9 and 10 respectively. 90

As seen in Figure 3, the numeral 11 designates the pulp feed or inflow pipe which communicates with the intake compartment 12. 95 This compartment is defined by a partition 13 whose lower end 14 is of curvate inturned configuration. Opposite to the partition 13 is a similar longitudinal partition 15 which simultaneously defines the effluent or exhaust 100

box or compartment 16 and a central separating chamber 17.

The cylinder is generally designated by the numeral 18, the couch roll by the numeral 19 and the scraping blade by the numeral 20. This blade functions as a chute for delivering the pulp by gravity into the box 16. The pulp is carried away through the conduit 21 to the point of storage (not shown).

10 As seen in Figures 4 and 5, the rotary cylinder comprises a tubular shaft or hub 22 whose enclosed surface is formed with a multiplicity of ports or perforations 23. The rim or surface of the cylinder is of open-work 15 grid-like formation and includes circumferentially spaced longitudinal rods 24 connected to the interposed radial spokes 25, said spokes being mounted through the medium of collars 26 on the shaft.

20 Around the rod 24 are inner and outer plies of screen, 27 and 28, of appropriate texture and gauge. This forms a porous separating surface. The ends 29 of the drum or cylinder are closed.

25 It is obvious that this porous surfaced hollow shaft drum and its appurtenances as a unit are confined within the area of the vat. The end portions 30 of the shaft however constitute journals which extend through the 30 stuffing boxes and are mounted in the bearings 9. In fact, the extremities 31 are flared and empty into open-top traps or receptacles 32 at opposite ends of the structure.

35 The water conducting pipes leading from these traps are denoted by the numerals 33 and these pipes lead to suitable points of deposit. Any suitable source of power is utilized for simultaneously rotating the cylinder and couch rolls 18 and 19 respectively.

40 As shown in Figure 2 for example, the numeral 34 designates the propulsion gear for the cylinder 18, this being mounted on the adjacent journal 30. In constant mesh with this is a pinion 35 mounted on the adjacent 45 end of the shaft for the couch roll 19, thus rotating these parts 18 and 19 in opposite directions and permitting the couch roll to pick up the pulp deposit on the surface of the cylinder.

50 In practice, the inflow of pulp laden material is supplied in the customary source and enters the vat 6 by way of the introductory pipe 11 and gravitates into the intake compartment 12. It flows from this compartment 55 12 into the chamber 17 where it is acted on by the rotating cylinder 18 and its companion couch roll or roller 19.

55 These unique expedients are calculated to act on the incoming mass of material in an efficient manner due to the fact that the influx enters the vat at right angles to the axis of rotation of the cylinder, the partition 13 acting as a baffle to cause indirect separation and to facilitate more efficient drainage of the water.

Figuratively, and broadly, the separating drum with its hollow central shaft forms a sort of a sluiceway for discharging the water into the collecting traps 32 at the opposite ends of the vat. It is understood, of course, that the entering fluid is of the customary fluidity.

It is further evident that the water passes through the porous surface of the drum and accumulates within the interior of the drum, being trapped by the imperforate head 29. The rotation of the drum however causes the water to pass through the perforations in the hollow shaft 22 and this effluent fluid is discharged through the open ends of the shafts into the traps and carried away by pipe 33.

Simultaneously the pulp adhering to the reticular surface of the drum is picked up by the couch roll and carried around and scraped off by the blade 20 and dumped into the compartment 16. It is then carried away by the conduit 21 to the place of storage (not shown).

It will be observed that the cylinder is sealed by imperforate heads at both ends so as to prevent any of the pulp, except such as passes through the fine reticular spacing or covering of the cylinder, for mixing with the extracted water which accumulates inside of the drum. The drum is of course partially submerged in the material to be conditioned or treated and when rotated at a predetermined speed, causes the relatively thick pulp to be delivered at varying degrees of density as desired, while the extracted water is conducted out through the hollow central shaft at both or either ends, as the case may be.

Particularly do I wish to emphasize a system of this kind wherein the inflow of pulp laden liquid is introduced into the vat at right angles to the axis of rotation of the cylinder, thereby permitting improved drainage of the water into the cylinder, and consequently, maximum deposit of pulp on the surface of the cylinder, at a point particularly where it leaves the liquid.

Then too, I emphasize the arrangement wherein the extracted water is accumulated within the interior of the drum and carried therefrom through the perforated shaft out through the ends of the vat and accumulated in appropriate collecting traps. Moreover, the arrangement is unique in that the water conducting shaft constitutes the means for rotatably supporting the cylinder within the vat and delivering the water to the end outside traps.

This perforated shaft is desirable because it equalizes the extraction process, and just as much pulp is carried off by the center portion of the cylinder as is carried off by the end portions thereof. Consequently this is a separating drum with a screening and sep-

arating surface of appropriate gauge, and the imperforate ends together with the perforated shaft is a predominating factor of novelty in this improved organization of parts.

It is thought that the description taken in connection with the drawings will enable a clear understanding of the invention to be had. Therefore, a more lengthy description 10 is thought unnecessary. While the preferred embodiment of the invention has been shown and described, it is to be understood that minor changes coming within the field of invention claimed may be resorted to if desired.

15 I claim:

1. In a structural assembly of the class described, in combination, an open-top vat, means for delivering the pulp-laden fluid to said vat, a rotary cylinder in said vat, said 20 cylinder having a reticular peripheral surface and closed end, a supporting shaft for said cylinder journaled for rotation in suitable bearings, said shaft being perforated and of hollow form, whereby to discharge 25 the separated water through the ends of the shaft uprights at the ends of the vat, bearings therein for the ends of the shafts, and receptacles located to the outer sides of the uprights into which the ends of the shaft 30 extend whereby said receptacles will receive the discharge from the shaft.

2. In a structure of the class described, in combination, an open-top vat provided at opposite ends with stuffing boxes, a tubular 35 shaft mounted for rotation in said stuffing boxes and having its opposite ends extending outwardly beyond the stuffing boxes, said opposite ends being open, that portion of the tubular shaft within the vat being 40 perforated, a separating drum mounted on said shaft and having imperforate heads and a reticular and adhesive surface, means for delivering the pulp-laden fluid into the vat and means for conveying the extracted pulp 45 from the vat, comprising a couch roll and a scraping blade, together with a pulp deposit box built in said vat, and a driving gear carried by said shaft and a pinion in mesh therewith for operating said couch roll whereby 50 to cause the cylinder and couch roll to operate in unison in opposite directions.

In testimony whereof I affix my signature.

GEORGE A. CUMBERLAND.
